UNITED STATES PATENT OFFICE.

PHILIP FOUKES, OF PITTSBURGH, PENNSYLVANIA.

SPlice FOR OIL-DERRICKS.

1,146,756.

Specification of Letters Patent. Patented July 13, 1915.

Application filed June 18, 1914. Serial No. 845,867.

To all whom it may concern:

Be it known that I, PHILIP FOUKES, a citizen of the United States, residing at Pittsburgh, in the county of Allegheny and State of Pennsylvania, have invented a certain new and useful Splice for Oil-Derricks, of which the following is a specification.

My invention relates to the construction of the joints of framed structures made of rolled structural steel and more particularly relates to the constructions of the joints between the framed members of derricks and towers made of rolled metal shapes.

Heretofore in fabricating such structures it has been the practice to use bolts to secure the parts together and the bolts used are necessarily of such size as to require angles of such minimum size in insuring good fabrication, that the weight of the structure is greater than necessary for the required strength and stiffness. As a result, it is difficult or impossible to compete with such structures using welded pipe for the legs or posts and in some cases, other parts of the structures as it is the practice to use old second hand, and therefore very cheap, pipe in making such structures.

Also in making such structures and using bolts to fasten the parts together, the cost of fabrication is very great owing to the large number of holes to be drilled and the large number of bolts employed in making the joints.

One object of my invention is to provide a splice of novel construction which is adapted for use in fabricating derricks, towers and similar structures from standard rolled metal shapes which is strong and durable and is easily and cheaply made and applied for use.

Another object of my invention is to provide a splice of improved construction having novel means whereby the number of holes necessary to punch and the number of bolts employed are reduced to a minimum, the necessity of using angles or other rolled metal shapes of excess weight is avoided and the cost of fabrication is materially reduced.

Still further objects of the invention will be apparent as the invention is more fully described hereinafter and particularly pointed out in the claims.

Referring now to the drawings forming part of this specification, Figure 1 is a side elevation of a portion of the leg of a derrick having a splice thereon as constructed and

arranged in accordance with my invention. Fig. 2 is a transverse section of the same, the section being taken on the line II-II 60 of Fig. 1.

In the accompanying drawings, the numeral 2 designates a rolled metal angle, (a standard commercial shape), forming one of the legs of a derrick and 3, 3, are girts, 65 which also are made of a rolled metal angle. Secured to the legs of the angle forming the derrick leg 2, above and below the girts 3 are the diagonals 4 and 5, the girts and diagonals being formed of rolled angles and 70 used to strengthen and stiffen the long angles 2 which form the derrick legs. The derrick may have three or more, (generally four) legs and in making some structures such as A frames there will be but two legs. 75

Encircling the angle 2 forming the derrick leg is a bent splice plate 6 having edge portions 7 and 8 bent into substantially parallel planes and having a series of (three being shown) registering holes in the so 80 formed flanges 7 and 8. Bolts 9 are inserted in the holes to tightly clamp the splice plate 6 in position on the derrick leg 2.

On the outer face of each of the flanges 85 7 and 8 is a clamping plate 10 having projecting lugs or ears 11, 12, 13. The side edges of the lugs or ears are bent to form flanges or ribs 14 which greatly strengthen and stiffen the lugs so as to prevent bending. 90

The clamping plates 10 have holes therein registering with the holes in the lugs or ears 7 and 8, the clamping bolts 9 for the splice plate also serving to secure the clamping 95 plates in position, in holding engagement with the girts 3 and diagonal braces 4 and 5.

Instead of using bolts to fasten the ends of the girts and diagonals to the derrick legs, a hemispherical projection 15 is pressed 100 or stamped in the ends of one leg of the angle forming the girts and diagonals (see Fig. 2) and pressed or stamped in the lugs or ears 11, 12, 13 on the clamping plates 10 are similar projections 16, the projections 15 being positioned within the hollow 105 recess or depression made in forming the projections on the ends of the angles 3, 4 and 5.

In fabricating a derrick or other structure 110 in accordance with my invention, the bent splice plates 6 are punched and bent to fit the particular size angle used for the derrick legs. The clamping plates 10 are

stamped or pressed to shape and provided with bolt holes for the bolts 9 and also with hemispherical projections or indentations 16. In the construction shown the indentations 16 are formed in each of the flanged lugs or ears of these clamping plates. Angles, of the proper size, are cut to length and projections 15 are provided on each end thereof for engagement with the indentations 16 in the lugs of the clamping plates. A splice plate 6 is then slipped over the angle 2 forming each derrick leg and a pair of clamping plates 10 loosely secured to the splice plate by means of the bolts 9. The angles 3 forming the girts and angles 4 and 5 forming the diagonals are then placed in position, with the ends thereof positioned between the lugs or ears 11, 12 and 13 of the clamping plates and adjacent surfaces of the splice plate 6. When so located, the projections 15 on the ends of the girts and diagonals extend into the indentations on the lugs 11, 12, 13 in holding engagement therewith.

The bolts 9 are then tightened so as to cause the splice plate to tightly grasp the derrick leg and also to cause the clamping plates to tightly grip the ends of the girts and diagonals, so that a strong and rigid structure is obtained.

The advantages of my improved construction will be appreciated by those skilled in the art.

The number of bolts and bolt holes necessary is reduced to a minimum, the parts are securely held in assembled position and the cost of fabrication is materially reduced.

My improved construction avoids the necessity of punching the angles forming the legs of the structure, thereby enabling lighter material to be used in the legs of the structure and by the reduction in weight further reducing the cost of building such structures.

Modifications in the construction and arrangement of the parts may be made within the scope of my invention as defined in the appended claims.

I claim:—

- 50 1. In a derrick or like structure, a splice joint comprising a splice plate encircling a leg of the structure, a clamping plate to fasten the bracing members to the leg of the structure, the end of said bracing members being positioned between the surfaces of the clamping plate and splice plate, said bracing members and at least one of said plates having coacting projections and depressions thereon to secure the bracing and plate against relative movement, and a bolt for clamping the splice plate and clamping plate in holding engagement with said leg.

2. In a derrick or like structure, a splice joint comprising a splice plate encircling a leg of the structure, a clamping plate to fasten a bracing member to the leg of the structure, the end of said bracing member being positioned between the surfaces of the clamping plate and splice plate, said bracing member and clamping plates having coacting depressions and projections thereon to fasten the bracing to the leg of the structure, and a bolt to fasten the splice plate and clamping plate in place on said leg.

3. In a derrick or like structure, a splice joint comprising a flanged splice plate encircling a leg of the structure, a clamping plate to fasten the bracing members to the leg of the structure, and a bolt engaging the flanges on the clamping plate and splice plate to clamp the plates on said leg of the structure, one end of said bracing members being positioned between the surfaces of the clamping plate and splice plate, said bracing members having projections on the ends thereof engaging registering depressions in at least one of said plates to fasten the bracing members to the leg of the structure.

4. In a derrick or like structure a splice joint comprising a flanged splice plate encircling a leg of the structure, a clamping plate to fasten the bracing members to the leg of the structure, and bolting means engaging the clamping plate and flanges on the splice plate to clamp and frictionally hold the plates on said leg of the structure, the end of said bracing members being positioned between the surfaces of the clamping plate and splice plate, and said bracing members having projections in the ends thereof engaging registering depressions in said clamping plates to fasten the bracing to the leg of the structure.

5. In a derrick or like structure a splice joint comprising a flanged splice plate encircling a leg of the structure, a clamping plate to fasten the bracing members to the leg of the structure, and bolting means engaging the clamping plate to clamp and frictionally hold the plates on said leg of the structure, the end of said bracing members being positioned between the surfaces of the clamping plate and splice plate, and said bracing members having projections in the ends thereof engaging registering depressions in said clamping plates to fasten the bracing to the leg of the structure.

In testimony whereof, I have hereunto set my hand.

PHILIP FOUKES.
